UNITED STATES PATENT OFFICE.

GEORGE P. JONES, OF EMPORIUM, PENNSYLVANIA.

MACHINE FOR MIXING EXPLOSIVES.

No. 882,114.

Specification of Letters Patent. Patented March 17, 1908.

Application filed April 22, 1907. Serial No. 369,602.

To all whom it may concern:

Be it known that I, GEORGE P. JONES, a citizen of the United States, residing at Emporium, county of Cameron, and State of Pennsylvania, have invented certain new and useful Improvements in Machines for Mixing Explosives, of which the following is a specification.

This invention relates to machines for mixing explosives.

The mixing of the ingredients of high explosives is a very dangerous operation and is frequently carried on by hand in order that it may be thoroughly carried out with minimum danger, but as hand-mixing is laborious and the out-put is limited, machines have been used for such purposes and the object of my invention relates to such machines.

20 The present invention has for its objects the provision of a machine for mixing explosives which will be safe, simple, readily controlled, and adapted for producing a large out-put in a given period of time.

25 Machines for mixing explosives have heretofore embraced, generally speaking, a mixing bowl or tub, stirrers or mixers adapted to operate therein, and some means for raising the stirrers or mixers from the tub or 30 receptacle or lowering them into it, and my invention has for its particular object the provision of novel means for raising and lowering the mixing or stirring devices so that they may be easily positioned within 35 the bowl or receptacle or raised from it, and to provide a novel construction and arrangement of the mixers and driving means, all of which are so arranged that particles of 40 the explosive cannot readily have access to the movable parts of the driving and lifting means. Whereas it has been proposed to use compressed air, or an air-lift, to raise the mixers from the bowl or tub and to lower them by the force of gravity alone, my invention 45 contemplates raising the mixers by the force of gravity, controlled by air pressure, and lowering them into the bowl or receptacle by a novel compressed air mechanism which is under a complete and delicate 50 control, permitting the mixers to be raised or lowered without shock and as slowly or as rapidly as may be desired.

The invention is set forth fully hereinafter

and its novel features are recited in the appended claims.

In the accompanying drawings:—Figure 1 is a front elevation; Fig. 1^a, a detail of the three-way valve; Fig. 2, a vertical section; Fig. 3, an end elevation; Fig. 4, a cross-section on line 4—4 of Fig. 1, the stirrers being lowered and turned crosswise; Fig. 5, a front elevation of a modification; Fig. 6, a front elevation of another modification; and Fig. 7, a cross-section on line 7—7 of Fig. 6, the stirrers being lowered.

The machine has a metal base 1 which may be supported on a suitable foundation, from which rise pillars 2 having cylinders 3 therein, to the lower ends of which lead branches 4 of a pipe 5 which may be supplied with compressed air or water pressure, compressed air being usually employed. The branches 4 are each provided with regulating valves 6 and the pipe 5 has a three-way controlling valve 7, (Fig. 1^a) having a supply pipe 5^a and exhaust pipe 5^b.

Supported upon the base 1 is the double mixing bowl, tub, or receptacle 8, which contains radiator pipes 9, through which hot water or steam is passed to keep the contents of the bowl or receptacle 8 at the proper temperature.

The pillars 2 are connected by a cross-head 10, which is braced from the base 1 by a brace 11. Extending in alignment with each other and secured to the pillars 2, are arms 12, which have bushings or bearings 13. Journalized in the bushings or bearings 13 are tubular shafts 14 of fork-like stirrers 15, while extending through the tubular shafts 14 are stirrer shafts 16, which are provided at their lower ends with stirrers 17 of fork-like form, the tines of the stirrers 17 extending upwardly to pass through the spaces between the tines of the stirrers 15. The pairs of stirrers lie side by side and are adapted to rotate so that the extremities of one pair do not quite touch the extremities of the other pair, which is more clearly seen from an inspection of Fig. 4. The numerals 18 designate belt-pulleys, which are loosely splined at 18^a on the shafts 16 above boxes 19 supported by the cross-piece 10 so that the shaft 16 can slip up and down through these pulleys and still be driven by them. Loosely 100 splined at 20^a on the tubular shafts 14 are

belt-pulleys 20, which are supported by the bushings or boxes 13 and permit free up and down slipping of the tubular shafts 14 while rotating the latter. Journaled in brackets 5 21 on brace 11 is a driving shaft 22 which may be driven by any suitable gearing 23 from a power shaft 24. The shaft 22 has secured thereto belt-pulleys 25 and 26. A belt 10 27 passes around pulleys 25 and 18. A belt 28 passes around pulleys 26 and 20. Slidable vertically within the cylinders 3 are pistons 29 which are provided with heads 30 that fit the interior of the cylinders, and they may be packed in any preferred manner. 15 The pistons 29 are of such weight that they more than counterbalance, that is, over-balance, the respective stirring means consisting of shafts 14 and 16 and stirrers 15 and 17, these pistons being connected to the respective 20 shafts 16 by cables 31 which pass around sheaves 32 and are swiveled at 33 to the upper ends of the shafts 16 and, in consequence, the tendency of these pistons is to raise the stirrers. Hence, when the pressure, whether 25 compressed air, water, or other motive fluid, is withdrawn from the cylinders 3, the pistons 29 will sink in the cylinders and raise the stirrers from the bowl or receptacle 8, according to the extent to which such fluid 30 pressure is relieved or withdrawn from these cylinders. When pressure is admitted into the cylinders 3 below the piston heads 30, the pistons are raised and the stirrers then descend into the bowl 8. The valves 6 and 7 35 afford the means whereby the pressure may be controlled to either simultaneously raise or lower the stirrers or to raise or lower one set independently of the other set, and the operator is thus enabled to raise or lower 40 either or both stirrers to any desired extent, without shock or jar and as fast or as slow as desired. The exhaust pipe 5^b permits the pressure in the cylinders 3 to be let off.

In order that the stirrers may not descend 45 so far within the bowl 8 that they will touch the bottom thereof (which would be exceedingly dangerous) suitable means may be provided for regulating the play of the pistons or the descent of the stirrers. A preferred 50 means is shown, which consists of movable abutments 34 through which the pistons 29 play and against which the heads 30 will strike, these abutments being secured in any one of a number of desired positions by bolts 55 35 which coöperate with toothed slotted plates 36. To insure that the mixers may remain in the bowl without the necessity for maintaining the motive fluid pressure against the piston heads 30, there are provided hand- 60 screws 37, which may be screwed in far enough to hold the piston heads 30 between them and the abutments 34.

In Fig. 5 I have illustrated a modification of the invention wherein a single piston and

cylinder are used. With this machine the sets of mixers must necessarily both rise and fall together. The piston is here shown at 29^a and the cable, which is shown at 31^a, passes over two sheaves 32^a and thence is provided with two strands 40 which are secured by bolts 41 to a cross-head 42, through which the shafts 16 loosely pass, the heads 16^a at the upper ends of shafts 16 holding the shafts in engagement with the cross-head 42, but permitting free turning of said shafts. 75 In Figs. 6 and 7 I have illustrated another modification of the invention, wherein the raising and lowering mechanism is the same as that shown in Fig. 5. Sprocket wheels 18^b, and a sprocket chain 27^a are shown as substitutes for the belt-pulleys 18 and belt 27. This machine is driven by a sprocket wheel on the shaft 22. In this modification of the machine, the stirrers are shown at 50, they being single and provided with laterally extending blades 51 which have their faces inclined or at an angle to the longitudinal axis of the shafts 16^a, said shafts being loosely splined to the sprocket wheels 18^b so that they may slip up and down therethrough. 90

I wish it understood that either single or compound stirrers, such as I have illustrated in the different figures, or other forms of stirrers may be associated with the raising and lowering means which I have invented, and that other modifications of the machines may be resorted to. To prevent shock or jar when the stirrers are lowered, suitable rubber faced collars 75 are employed. 95

Having thus described my invention, what I claim as new and desire to secure by Letters Patent, is:

1. In a machine for mixing explosives, the combination with a mixing receptacle, of a mixer adapted to be lowered into or raised from the mixing receptacle, means for overbalancing said mixer tending to raise it, and means for causing the lowering of the mixer into the receptacle against the action of said overbalancing means. 110

2. In a machine for mixing explosives, the combination with a mixing receptacle of a mixer, motive fluid operated means for causing the lowering of the mixer into the mixing receptacle, and means for automatically raising the mixer on the release of the fluid pressure. 115

3. In a machine for mixing explosives, the combination with a mixing receptacle, of a mixer, motive fluid operated means for causing the lowering of the mixer into the mixing receptacle, and overbalancing means for automatically raising the mixer on the release of the motive fluid pressure. 120

4. In a machine for mixing explosives, the combination with a mixing receptacle and a mixer, of a cylinder, an overbalancing piston playing in the cylinder, a wheel, and a flexi-

ble connection between the overbalancing piston and the mixer which passes over the wheel whereby the piston tends to raise the mixer.

5. In a machine for mixing explosives, the combination with a mixing receptacle, and a mixer, of a vertical cylinder, an overbalancing piston playing in the cylinder, a wheel, a flexible connection between said piston and

the mixer which passes over the wheel, and 10 fluid operated means for raising said piston.

In testimony whereof, I hereunto affix my signature in presence of two witnesses.

GEORGE P. JONES.
